Primary Examiner — Philip S Hyder*Assistant Examiner* — Sydney Buffalow(74) *Attorney, Agent, or Firm* — Workman Nydegger**CLAIM**

The ornamental design for an eyeglass display, as shown and described.

DESCRIPTION

FIG. 1 is a perspective view of an eyeglass display; FIG. 2 is a top plan view of the eyeglass display as shown in FIG. 1;

FIG. 3 is a front elevational view of the eyeglass display shown in FIG. 1;

FIG. 4 is a bottom plan view of the eyeglass display as shown in FIG. 1;

FIG. 5 is a back elevational view of the eyeglass display as shown in FIG. 1; and,

FIG. 6 is a left side elevational view of the eyeglass display as shown in FIG. 1, with the right side being a mirror image thereof.

The broken lines are for illustrative purposes only and form no part of the claimed design.

UNITED STATES PATENT AND TRADEMARK OFFICE
CERTIFICATE OF CORRECTION

PATENT NO. : D663,971 S
APPLICATION NO. : 29/283411
DATED : July 24, 2012
INVENTOR(S) : Raile

Page 1 of 1

It is certified that error appears in the above-identified patent and that said Letters Patent is hereby corrected as shown below:

Title Page 2, Left-hand Column

Line 51 (Patent No. D286,462), change "Sender" to --Sender et al.--

Line 59 (Patent No. D319,156 S), change "8/1991" to --8/1992--

Title Page 2, Right-hand Column

Line 40 (Patent No. 996,818), delete the line beginning with "996,818 A"

Line 43 (Patent No. 420,533), change "420,533" to --D420,533--

Title Page 3, Left-hand Column

Line 17 (Patent No. 6,491,458), change "6,491,458" to --6,492,458--

Line 23 (Patent No. D479,126), change "9/2003" to --12/2002--

Title Page 3, Right-hand Column

Line 35, change "C1 Pocket" to --Pocket--

Under OTHER PUBLICATIONS, insert the following reference,

--Sun Optics, Inc. v. FGX International, Inc. (U.S. District Court Delaware), Answer, Affirmative Defenses, and Counterclaims of Defendant FGX International, Inc. to Plaintiff's Amended Complaint, August 16, 2007, 11 pages.--

Signed and Sealed this
Twenty-fifth Day of June, 2013

Teresa Stanek Rea
Acting Director of the United States Patent and Trademark Office
